UNITED STATES PATENT OFFICE.

ROBERT G. ADAMS, OF NEW YORK, N. Y.

PROCESS FOR REMOVING SHINE AND GLOSS FROM WORN FABRIC.

Application filed January 28, 1926. Serial No. 84,427.

This invention relates to a process for removing shine and gloss from worn fabrics.

The primary object of the invention is the development of a process for removing the shiny or glossy appearance from fabric by subjecting the nap of the fabric to a gentle, non-injurious treatment which will raise the same.

A further object of the invention is to provide novel means for carrying out certain steps of the said process.

Other objects and advantages of the invention will be apparent during the course of the following description.

In the accompanying drawing forming a part of this specification and in which like numerals are employed to designate like parts throughout the same,

Figure 1 is a perspective view of a novel form of brush employed in carrying out this process,

Figure 2 is a bottom plan view of the brush structure shown in Fig. 1,

Figure 3 is a central longitudinal sectional view of the structure shown in Figs. 1 and 2, and

Figure 4 illustrates diagrammatically the steps of the process wherein the brush structure is employed.

It is well known by those skilled in the art that the glossy or shiny appearance or surface which develops on many fabrics when used in the form of wearing apparel is caused by the flattening or crushing of the nap of the said fabric against the body of the latter. To remove this glossy or shiny appearance, it is necessary to rejuvenate the nap of the fabric by freeing the same from the body of the cloth and raising it so that it will stand up with each strand of the nap separated.

The various stages or steps performed during the carrying out of this improved process may be described as follows and the diagrammatic illustration set forth in Fig. 4 will illustrate a portion of the same. The fabric F which has been worn shiny is first spread or stretched upon a supporting surface, such as a table or pressing board. It is desirable, if convenient, to clamp the fabric to the support so that any shifting or wrinkling of the material will be prevented. The dot and dash line 5, appearing in this figure is intended to represent the margin of the portion of the fabric F being acted upon. It is not to be understood, however,

that the circular form of this line 5 constitutes any part of the process because it merely illustrates diagrammatically the margin of the portion being treated and, in actual practice, this margin will be irregular. The portion of the fabric being treated should first be moistened with a clean sponge and water, taking care that the material is not soaked, but merely thoroughly dampened. A granular composition, having as its base a silicate and a special wood fibre, should then be sprinkled over the moistened surface. A brush, of the type illustrated in Figs. 1 to 3 inclusive and which consist primarily of a rubbing surface of ribbed contour and of fabricated material, should then be employed for massaging or rubbing the moistened surface covered with the above referred to composition. The reverse arrow lines 6 arranged in concentric circles upon the portion of the fabric covered with the granular material 7 are intended to illustrate the movement of this massaging brush in carrying out this particular step of the process. The brush should be grasped firmly in a hand of the operator and with forward and reverse circular motion, the portion of the cloth being treated should be rubbed or brushed until the shine or gloss is removed. Care should be taken to keep the granular material 7 beneath the brush during this rubbing operation.

After the shiny or glossy appearance has been removed, the granular material 7 should be removed from the fabric by means of a whisk broom, or the like. The treated cloth should then be left until it becomes thoroughly dried when any remaining particles of the granular material may be removed by further brushing the fabric. The final step in this process consists of passing steam through the treated portion of the cloth. This step may be performed in any desired manner, but for ordinary household use, a dampened pressing cloth and a hot iron may be employed, the dampened cloth being placed upon the fabric and the iron passed over the pressing cloth for causing steam to be created which will be forced through the material.

After these various steps have been properly performed, it will be found that the glossy or shiny appearance has left the fabric and will not return any quicker than such a shiny or glossy appearance will appear on new fabric.

The specific type of fabric massaging or rubbing brush illustrated in detail in Figs. 1 to 3 inclusive consists of a back 8 having suitable longitudinal edge grooves 9 to facilitate grasping the same and a clamping strip 10 which is reduced in thickness intermediate its ends by the cutting of a longitudinally elongated groove 11 in its inner face. The clamping strip 10 is secured to the back 8 in any desired manner, such as by the screws 12 clearly illustrated in Figs. 2 and 3. The operating surface of the brush is provided by winding a length of woven rope 13 around the reduced portion of the clamping strip 10 to provide the ribbed fabricated surface clearly illustrated in Fig. 2. The ends 13^a of the length of rope 13 are prevented from becoming loose by being clamped between the strip 10 and the back 8, as are the other convolutions of the rope, as clearly illustrated in Fig. 3.

The granular composition previously referred to, and described in connection with the showing in Fig. 4 wherein the composition is designated by the reference character 7, consists of a silicate salt and special wood fibre body which are mixed in proper proportions with many different fabric softening and treating ingredients. It will be remembered that the moistening of the fabric during the carrying out of the process will also provide a certain amount of water which will mingle with the wood fibre and silicate salt. The wood fibre will become impregnated with the silicate and other ingredients and acts as a carrier for the same. The silicate salt referred to is deemed to mean silicate broadly consisting of sand of a certain degree of fineness, granulated marble, granite or sand stone.

Having thus described the invention, I claim:—

1. The herein described process of raising the nap and removing the shine from the nap surface of fabric which consists in moisten-

ing the fabric, then brushing a granular material over the moistened surface of the fabric, then removing the granular material, and finally passing steam through the fabric.

2. The herein described process of raising the nap and removing shine from the nap surface of fabric which consists in moistening the fabric, then brushing a granular material over the moistened nap surface of the fabric in reverse circular directions, then removing the granular material, and finally pass steam through the fabric.

3. The herein described process of raising the nap and removing the shine from the nap surface of fabric which consists in moistening the fabric, then brushing a granular material having silicate salt as a basic ingredient over the moistened nap surface of the fabric, then removing the granular material, and finally passing steam through the fabric.

4. The herein described process of raising the nap and removing the shine from the nap surface of fabric which consists in moistening the fabric, applying a granular material having silicate as a basic ingredient and wood fibre as a carrier to the nap surface of the moistened fabric, then brushing the material over the moistened nap surface of the fabric by means of a ribbed fabricated member moved in reverse circular directions, then brushing the granular material from the fabric, and finally steam pressing the fabric.

5. Apparatus for use in removing the shine from fabric comprising a two-part body, and a length of woven rope wound around one part of said body and secured thereto by connecting together said parts of the body with the ends and portions of the convolutions of the rope clamped between said parts.

In testimony whereof I affix my signature.

ROBERT G. ADAMS.
